CLAIM

The ornamental design for a cosmetic container with cap, as shown and described.

DESCRIPTION

FIG. 1 is a top plan view of a cosmetic container with cap embodying our new design;

FIG. 2 is a perspective view thereof;

FIG. 3 is a left view thereof;

FIG. 4 is a front view thereof;

FIG. 5 is a right view thereof;

FIG. 6 is a back view thereof; and,

FIG. 7 is a bottom plan view thereof.

The broken lines shown in the drawings are for environmental purposes only and form no part of the claimed design.
